UNITED STATES PATENT OFFICE.

MELVILLE J. FENWICK, OF COTTAGE GROVE, OREGON.

WASHING-MACHINE.

SPECIFICATION forming part of Letters Patent No. 251,201, dated December 20, 1881.

Application filed September 8, 1881. (Model.)

To all whom it may concern:

Be it known that I, MELVILLE J. FENWICK, of Cottage Grove, in the county of Lane and State of Oregon, have invented a new and Improved Washing-Machine, of which the following is a specification.

The invention consists in a washing-machine provided with a rubbing-cylinder attached to the lower ends of two connected rocking arms 10 loosely mounted on a shaft of the machine, which arms also carry at their lower end an additional rubbing-block, on which the clothes are held by a clamp-bar provided with two arms fitting in sockets containing springs for 15 pressing the clamp-bar on the block, as hereinafter fully described.

In the accompanying drawings, Figure 1 is a plan view of my improved washing-machine, parts being shown in section on the line *y y*, 20 Fig. 2. Fig. 2 is a longitudinal sectional elevation of the same on the line *xx*, Fig. 1. Fig. 3 is a plan view of the under side of the rubbers.

Similar letters of reference indicate corresponding parts.

Two rocking arms, A, are connected at their upper ends by a transverse bar or handle, B, and are provided at or near their middle with slots C, through which the shaft D of the washing-machine frame passes. A rubbing-cylinder, E, provided with spiral grooves, is attached to the lower end of the rocking arms A, and a rounded spirally-grooved rubbing-block, F, is rigidly attached to the lower ends 30 of these arms and adjoining the rubbing-cylinder E. A clamp-bar, G, sliding in slots G' in the arms A, rests on the top of the block F, and is provided at the ends with vertical arms H, fitting in sockets J on the inner sides of the 35 arms A, and containing spiral springs K, which press these arms H downward, thus pressing the clamp-bar G upon the block F. The bar G is provided with a handle-knob, L, for raising it. A series of rollers, M, provided 40 with spiral grooves N, are loosely mounted on a segmental concave line in a frame, O, fitting in the washing-box P.

The operation is as follows: The clamp-bar G is raised and the articles to be washed 50 are placed on the rubbing-block F, on which they are held by the clamp-bar G. If the arms

A are rocked, the articles will pass under the rubbing-cylinder E and the block F, and will be rubbed on the rollers M. During this rocking motion the arms A are raised occasionally 55 to place the articles in another position under the rubbing-blocks, the slots C permitting of such movement of the arms A. As the rollers M and the rubbers are grooved spirally they will move the articles in the direction of the 60 length of these rollers in addition to the movement over the rollers. The clothes or other articles are only rubbed and are not pounded, and will not be torn or damaged by this machine. If the shaft D is withdrawn, the arms 65 A and the frame O can be removed from the box P.

Having thus fully described my invention, I claim as new and desire to secure by Letters Patent—

1. In a washing-machine, the combination, 70 with the rocking arms A, provided with the rubbers E F, of the spring-actuated clamp-bar G, resting on the top of the rubber F, substantially as and for the purpose set forth. 75

2. In a washing-machine, the combination, 80 with the rocking arms A, of the rubbers E and F, attached thereto, the clamp-bar G, provided with arms H, the sockets J, the springs K, and the rollers M, substantially as herein shown and described, and for the purpose set forth.

3. In a washing-machine, the combination, 85 with the rocking arms A and the rollers M, of the cylindrical rubber E, the rubbing-block F, and the clamp-bar G, resting on the top of the said rubbing-block, substantially as and for the purpose set forth.

4. A washing-machine made substantially 90 as herein shown and described, and containing the following elements, to wit: rocking arms A provided with slots C, and loosely mounted on a shaft, D, rubbers E and F, attached to the arms, a clamp-bar, G, provided with arms H, fitting in sockets J, containing springs K, and rollers M, mounted in a frame, O, fitting in the box P, as set forth. 95

MELVILLE JAY FENWICK.
